PATTERNING MECHANISM FOR KNITTING MACHINES

Leslie Herbert Leedham, Leicester, England, assignor to Wildt and Company Limited, Leicester, England, a British company

Application July 13, 1937, Serial No. 153,439
In Great Britain July 18, 1936

20 Claims. (Cl. 66—14)

This invention relates to pattern mechanism for knitting machines, and has reference to pattern mechanism applicable to knitting machines of the independent needle type for selective operation of the needles to produce pattern, design or like effects by stitch variation, thread selection and any other of the known methods.

The invention concerns pattern mechanism of the type including selecting elements or bits adapted to be pivotally mounted in the needle grooves or tricks or in corresponding grooves or tricks in an associated bed or carrier, said selecting elements or bits having selecting butts or like formations in different positions lengthwise thereon, and selecting cam means adapted to operate selectively upon the said butts or like formations under the control of a pattern controlling device or unit for the purpose of determining which of the needles shall be subsequently caused to move endwise by associated actuating means for patterning or designing purposes.

The pattern mechanism provided by this invention is applicable to knitting machines of the independent needle type generally, i. e. to both circular knitting machines and flat knitting machines, rib and plain, and, in the case of circular knitting machines, to both machines of the rotary cylinder type and machines of the stationary cylinder type.

It is primarily the intention to apply the improved patterning mechanism to circular knitting machines of the double axially opposed, e. g. superposed, needle cylinder type wherein independently slidable double-ended needles are cam operated through the medium of sliders by means of which transfer of needles from one cylinder to the other can be effected automatically, such as for changing from plain knitting to rib knitting, and vice versa, or from one rib combination such as 1/1 to another, e. g. 2/2 or some other broader rib, and vice versa. In this connection the invention is applicable to superposed cylinder machines which operate simply with circular motion for knitting tubular fabric, garments, or garment lengths such as for pullovers, slipovers, jumpers and the like, as well as to machines of the same type which are adapted to operate with rotary motion to produce circular work, and with reciprocatory motion to produce pouches, as for example in the manufacture of seamless hosiery, the principal purpose of the application of the invention to machines of this characteristic type being to effect transference of needles from one cylinder to the other, for example from the plain cylinder to the rib cylinder, in a pattern con-

trolled selective manner in order to produce a diversity of fancy rib and like effects in the fabric or articles produced on such machines. For instance, the improved pattern mechanism may be applied advantageously to a seamless hose machine of this type so as to enable stockings, half hose, socks and like articles having tops either of ordinary rib or with rib pattern or fancy effects, and leg and foot portions which are also similarly patterned to be produced in a continuous manner. The said mechanism may also be advantageously applied to machines adapted to produce tubular body garments or garment lengths, for the purpose of producing a garment or garment length with a rib bottom of ordinary (2/2) or fancy character, and a fancy body portion. The invention is not limited in this respect, however, as the said pattern mechanism may be applied to machines of the same type and to circular knitting machines of other types for the purpose of exercising pattern controlled selective operation of needles for any other known purposes, such as stitch variation or thread selection, or both.

According to the present invention there is provided a pattern mechanism of the type before referred to in which each of the selecting elements or bits is adapted to have operative engagement or equivalent relationship with a companion needle, or with an associated slider or an intermediate jack at or adjacent to its tail end, whereby when such elements or bits are acted upon by the selecting cam means and make contact with the actuating means endwise movement of the corresponding needles necessary for the particular purpose in view is effected.

The present invention is distinguished from previously proposed pattern mechanisms of the type concerned by reason of the fact that the opposite, e. g. upper, ends of the selecting elements or bits do not at any time have operative engagement or relationship with the said needles, sliders or jacks.

In the accompanying drawings,

Figure 1 is a plan view, partly in section, of so much of a circular knitting machine of the superposed needle cylinder type as is necessary to illustrate the application thereto of the present invention.

Figure 2 is a vertical sectional view of the same taken on the line II—II of Figure 1.

Figure 3 is a detail vertical sectional view illustrating a selecting element or bit and an associated needle operating slider in the normal position.

Figure 4 is a similar view showing the positions occupied by a selected element or bit and the

associated slider when they have been acted upon by the actuating cam as will be hereinafter more fully described.

Figure 5 is another similar view showing the 5 manner in which an unselected element or bit moves idly when acted upon by the said actuating cam.

Fig. 6 is a development of the cam system 10 associated with the bottom cylinder of the machine.

Figure 7 is a detail sectional view taken on the line VII—VII of Figure 1.

Figure 8 is a vertical sectional view illustrating the modification aforesaid.

15 Figure 9 is a perspective view drawn to an enlarged scale of a return cam employed in conjunction with the modified form of pattern mechanism shown in Figure 8.

Like parts are designated by similar reference 20 characters throughout the drawings.

Referring to the drawings, 1 designates the bottom needle cylinder, 2 the opposing top cylinder (Figure 4) 3 the needle actuating sliders and 4 one of the independently slidable double-ended 25 needles which are adapted to be transferred from one cylinder to the other. As will be seen, the cylinders are vertically disposed and the pattern mechanism now to be described is applicable for use below the sliders in the bottom needle cylinder 1. The said mechanism includes selecting 30 elements or bits 5 each of which is provided with one or more frontal selecting butts such as 6 and with a rearwardly projecting butt 7 or like formation at the lower end. Conveniently each element or bit 5 is furnished on its front edge with a series of frangible selecting butts which can be broken away to provide a butt or butts in the required position or positions. Each element or bit, moreover, is provided as at 8 with a fulcrum 40 point or equivalent at the back at or near the upper end. Associated with the selecting elements or bits 5 are jack-like extensions 9, one on each slider, to be acted upon for patterning purposes, each of these extensions being of a relatively thin character and formed at the lower 45 extremity with a portion 10 which splays outwardly to a slight extent. Each extension 9, together with the slider of which it forms a part, is located at the back or in the bottom of the 50 groove or trick 11 in which it is to work and the companion selecting element or bit 5 works in the same groove or trick with its fulcrum point 8 in contact or engagement with the front edge of the extension or with the corresponding edge of 55 that portion of the corresponding slider adjacent to the upper end of said extension. The grooves or tricks 11, which, in the specific example illustrated are continuations of the customary needle tricks 12 in the cylinder 1, are made comparatively deep to accommodate both the slider extensions 9 and the elements or bits 5. The form of 60 a needle trick and its continuation is shown more clearly on the left-hand side of Figure 2. Thus the grooves or tricks 11 are provided in an extension 13 of the bottom needle cylinder 1. Alternatively, however, the said grooves or tricks 65 may be provided in a supplementary cylinder suspended from or attached co-axially to the bottom cylinder. The arrangement is such that the 70 jack-like extensions 9 have the portions 10 thereof located above the rearwardly projecting butts 7 or like formations, and normally the lower ends of the selecting elements or bits 5 project forwardly from the grooves or tricks 11 with the 75 butts 7 out of alignment with the extensions 9.

The selecting elements or bits, when in the normal position indicated in Figure 3, are prevented from falling out of the grooves or tricks 11 by a carrier ring 14 (the primary purpose of which is hereinafter specified) and a sectional 5 ring 15 attached to the inside of the bottom cam box 16. In this connection each of the selecting elements or bits, besides being provided with a tail portion 17 which normally rests against the inner edge of the ring 14, is formed at its upper 10 end with a reduced portion 18 the front edge of which rests at all times against the inner surface of the ring 15 while the adjacent shouldered portion 19 of the selecting element or bit permanently engages beneath the lower edge of the said last 15 mentioned ring.

For selectively operating the selecting elements or bits 5 there is provided a bank of as many spring controlled selecting cams such as 20 as the maximum number of butt positions provided 20 on any single element or bit, and a pattern controlling unit 21 in the form of a drum, cylinder or like body furnished, as shown, with cam actuating pins 22 or, alternatively, with screws or selector strips, removable and interchangeable 25 for producing different patterns. In the specific example illustrated the pattern controlling unit is mounted on a vertical spindle 23 and operated by cam operated pawl and ratchet mechanism.

As will be seen, the spindle 23 is carried by a 30 bracket 24 secured to the bottom plate 25 or equivalent part of the machine and the drum or cylinder 21 has attached thereto a ratchet wheel 26 adapted to be engaged by a spring-controlled pawl 27 (spring not shown). This pawl is carried by one arm of a two-armed lever 28 which is mounted to turn on the axis of the drum or cylinder 21 and furnished on its other arm with a roller 29 adapted, as is customary in pattern controlling mechanism of this character, to be 40 acted upon by cam means rotating in time with the machine. Thus, whenever the machine is in operation, the lever 28 is continuously oscillated to impart to the pawl the necessary strokes to rack round the drum or cylinder 21 in timed 45 relation with other moving parts of the machine. The drum or cylinder 21 is surrounded in the usual way by a cylindrical casing 30 which is appropriately slotted both in the region of the selecting cams 20 and the pawl 27. The selecting cam means may be of any other suitable form and arrangement.

The actuating means aforesaid conveniently consist of an upthrow or jack raising cam 31 which is formed or provided on the carrier ring 14 55 and is of the shape shown more clearly in Figure 6. In this specific example of the invention the selecting elements or bits 5 and the actuating cam 31 are formed and arranged so that all of the said elements or bits make contact with the 60 cam but only those which are selected, i. e. engaged by an operative selecting cam 20 and pressed inwards so that they pivot backwards on their fulcrum points 8 and are thereby positioned in operative relationship with the associated jack-like extensions 9, as indicated on the right-hand side of Figure 2, function to operate the corresponding needles 4, while the remainder, i. e. those which occupy the normal inoperative position of Figure 3, are merely moved idly by the 70 said cam as shown in Figure 5 so that they do not affect the associated needles. The needles which are operated in the manner just described are caused or subsequently caused to function for patterning or designing purposes. The portion 75

of each selecting element or bit which is acted upon by the actuating cam 31 is designated by the reference numeral 32 and, as will be seen, this portion is in the form of a frontal butt or shoulder 5 and formed at its lower edge with a notch or recess 33, the purpose of which is to prevent the element or bit—in the event of it being unselected at the selecting point S—from accidentally moving into operative position with its 10 rearwardly projecting butt 7 or like formation immediately beneath the portion 10 of the corresponding jack-like extension 9. As will be readily understood, the arrangement is such that immediately an unselected element or bit 5 commences to travel over the actuating cam 31 the 15 upper edge of the latter enters the notch or recess 33 and thereby holds the element or bit in its normal inoperative position while it is being raised (see Figure 5). The upper edge of the cam 31 and the lower edges of portions 32 aforesaid may 20 be and preferably are slightly inclined suitably to effect satisfactory engagement between these parts. For the same reason the upper edges of the rearwardly projecting butts 7 and the lower 25 extremities of the jack-like extensions 9 are similarly inclined.

Cam means are provided for action upon the selected selecting elements or bits 5 to restore same to normal position preparatory to a re-selection being effected. In the example illustrated the said means include a cam or, as shown, a cam surface 34 for returning all selecting elements or bits to the normal level after they have passed over the actuating cam 31 and a cam, 30 such as 35 (Figure 1) located behind the elements or bits at or adjacent to their tail ends for pushing previously selected elements or bits outwards preparatory to re-selection. As will be seen, the cam surface 34 is formed on the section 15' of the ring 15 and the latter is cut away as at 36 to permit the selecting elements or bits to rise as the portions 32 pass over the cam 31. The surface 34 depresses the elements or bits by reason of the engagement with said surface of 35 the shouldered portions 19 of the elements or bits. The cam 35 is formed or provided on the carrier ring 14 and is formed with a curved face 37 which is disposed immediately beneath the cam surface 34 and adapted to act on the rear edges of the tail portions 17 of the elements or bits to move the latter outwards in the manner indicated in dot-and-dash lines in Figure 1.

All the elements or bits, after passing the cam 31, are preferably held in the normal inoperative position until they again approach the selecting point S. Conveniently for this purpose the carrier ring 14 is formed with an annular recess or track 38 for reception of the tail portions 17 of the selecting elements or bits. The 40 idea is that the said tail portions of unselected elements or bits pass directly from the actuating cam 31 into the track or recess 38 while the corresponding portions of selected elements are directed into the said track or recess by the cam 35. In the particular construction shown it will be noted that there is a gap a in the annular recess or track 38 but this is only made for constructional considerations and has no other significance. Immediately in advance of the 45 selecting point S the said track or recess is provided between the carrier ring 14 and a cam 39 attached thereto.

Conveniently the carrier ring is made up in sections and is attached, e. g. by means of screws, 50 to an annular flange 40 provided on the inside

and at the lower end of an auxiliary cam box 41 which is interposed between the lower end of the cam box 16 and the bottom plate 25.

When, as in the example now being described, the improved pattern mechanism is applied to 5 the production of fancy rib and like effects by selective needle transference in a machine of the characteristic type herein before referred to, the said mechanism is preferably associated with the plain cylinder as already mentioned. The invention is not to be regarded as limited in this respect, however, as by simple inversion of the parts, where necessary, the said mechanism may be used in conjunction with the rib cylinder.

The pattern mechanism may be employed to 10 effect complete transference of selected needles from one cylinder to the other. Alternatively, and as shown, the said mechanism can be used simply to initiate such transference of selected needles, the action in this instance being completed by a transfer cam 42 into the range of which the sliders 3 of selected needles are raised by the pattern mechanism. The customary transfer butts 43 are provided on the sliders 3 and it is these butts which are acted upon by the 15 cam 42. The manner in which the selection takes place is indicated in Figure 6. The customary knitting and associated cams of the bottom cam system are shown at K and the existing transfer cam 44 is adapted to be moved in 20 the usual manner to and from an operative position for normal transfer purposes by any conventional means. In any event, the sliders are raised from a prearranged level to an extent sufficient for the purpose in view. The pattern 25 mechanism may be employed to produce purl designs by needle transference and the expression "fancy rib and like effects" should therefore be regarded as including such designs.

As will be understood, needles corresponding 30 with sliders which are not acted upon by the pattern mechanism during the production of fancy rib or like effects are caused to knit by the corresponding cams, while those needles which are transferred as the result of the selective action 35 of the patterning mechanism are caused to knit by the knitting cams associated with the opposing cylinder.

When the pattern mechanism is employed for patterning by other methods such as stitch variation, e. g. by producing tuck, miss-stitch or float effects, the needles may be raised from a non-knitting level to a tucking level or to a clearing height, or from tucking position to clearing height according to the effect to be 40 produced.

Means may be provided for automatically nullifying or preventing selective action by the pattern mechanism for predetermined intervals to produce fabric with plain or ordinary ribbed sections or areas as well as sections or areas containing fancy rib, such as miss-stitch, float and like effects. Conveniently for this purpose a cam is located between the selecting point and the actuating means behind the selecting elements or bits at or adjacent to their tail ends, 45 said cam being normally inoperative but adapted to be rendered operative for predetermined intervals for the purpose of causing all selected elements or bits to be pushed outwards again. In the specific example shown in the drawings a nullifying cam for this purpose is indicated at 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

cam being moved or permitted to move upwards from its normal inoperative position, indicated in Figures 6 and 7, to its fully operative position, indicated at 45' in Figure 7. The cam 45, moreover, has a suitably curved operative face 40, is formed or provided on a slide 47 and projects into the auxiliary cam box 41. The slide 47 is attached in any suitable manner to the upper end of a short vertical spindle 48 which is adapted for sliding movement in the bottom plate 25. A compression spring 49 is interposed between the underside of the slide and the top surface of the said bottom plate and the slide is normally held depressed against the spring action with the nullifying cam 45 inoperative by a bar or lever 50. Conveniently this bar or lever is pivoted in a small bracket 51 attached to the bottom plate and adapted to be moved, i. e. turned on its pivot, to permit the slide to move upwards to render the cam 45 fully operative by means of any suitable form under the control of the existing controlling mechanism of the machine or/and an auxiliary timing or pattern chain or equivalent suitably controlled and operated. For example, and as shown, the bar or lever 50 is connected at one end to a link 52 which is adapted to be operated from a timing or pattern chain and at the other end to another lever 53 which is pivoted at 54 and operable by or from the usual cam drum of the machine to move the bar or lever 50 in the required manner and at the appropriate times. This arrangement enables the nullifying cam 45 to be controlled either by the cam drum or by the timing or pattern chain, as may be required, at different stages in the production of a knitted article, e. g. a stocking. A small fixed plate 55 is provided to guide the slide 47 when it is moved from one plane to another.

Means may be and preferably are also provided for restricting patterning to prearranged portions (circumferentially) of the knitted fabric, such for example as the instep of a stocking, half hose, sock or like article.

For example, the actuating cam 34 may be movably arranged and automatically moved to and from its operative position at predetermined intervals by means of any conventional form. Preferably for this purpose, however, some of the elements or bits 5, for example substantially one half of the series, may be provided with relatively long tail ends and the remainder with shorter tail ends extending beyond the aforesaid rear butts or feet, and a return cam movable into different planes under pattern control may be provided for action on either the long or both long and short tails so as partly or wholly to nullify the selective action according to requirements. A long tail end is indicated at 17' and a shorter tail end at 17'' in Figure 3 and in the example illustrated the nullifying cam 45 is employed for the purpose just described. Thus the bar or lever 50 is operated at the appropriate times to cause the cam 45 to occupy one of three positions, viz. a normal inoperative position where it is clear of the tail ends of all the selecting elements or bits, an intermediate position wherein it can act on the long tails alone for pushing outwards those of the long tailed selecting elements or bits which are selected at S, and a fully operative position (indicated at 45' in Figure 7) in which it can act on both long and short tails so as wholly to nullify the selective action.

An embodiment of the invention similar to

that just described could, of course, be applied to a construction in which each of the selecting elements or bits is adapted to act directly on the corresponding needle or upon an intermediate jack which is either separate from or formed in one piece with said needle.

Again, instead of providing jack-like extensions 9 on the sliders 3 as in the specific example hereinbefore described, separate intermediate jacks may be provided between said sliders and the selecting elements or bits.

In the modification illustrated in Figures 8 and 9 applicable for use below the needles such as 56 in a vertically disposed needle cylinder 57, or the sliders in the bottom needle cylinder of a machine of the superposed needle cylinder type, the selecting elements or bits 58 are provided each with one or more frontal selecting butts 59 and, at the lower end, with a rearwardly projecting butt or like formation 60 of the form shown. Each selecting bit 58 is provided with a fulcrum point 61 or equivalent at the back at or near the upper end. Associated with the selecting elements or bits are slidable intermediate jacks such as 62, one for each needle (or slider) to be actuated upon for patterning purposes, each of these jacks being of a relatively thin character having enlarged ends 63 and 64. Each jack is located at the back or in the bottom of the groove or trick in which it is to work and the companion selecting element or bit works in the same groove or trick with its fulcrum point or equivalent in contact or engagement with the front edge of the jack. Spring retaining bands or rings 65 and 66 are provided for the purpose of preventing the jacks and selecting elements or bits from falling out of the grooves or tricks. The arrangement is such that intermediate jacks 62 have their upper ends 63 located beneath the lower ends of the needles 56 (or needle actuating sliders) and their lower ends 64 located above the rearwardly projecting butts or like formations 60, and normally the lower ends of the selecting elements or bits project forwards from the grooves or tricks with the butts or feet out of alignment with the jacks.

In this example the actuating cam means consist of an upthrow or raising cam 67 suitably disposed for action upon the lower ends of selected selecting elements or bits 58 whereby the latter are raised and correspondingly raise the associated needles 56 through the medium of the intermediate jacks 62 which may therefore be regarded as lifting jacks, so that the said needles are caused, or subsequently caused to function for patterning or designing purposes.

By means of this arrangement when a selecting element or bit 58 is selected it is pressed inwards at the lower end to bring rearwardly projecting butt or foot 60 under the lower end of the companion lifting jack 62 and into the range of the upthrow or raising cam 67 so that as a result the selecting element or bit, lifting jack and needle are raised as and for the purpose intended. The cam means for restoring selected selecting elements or bits to normal position preparatory to re-selection being effected are indicated at 68 and are constructed and arranged for action on the selecting elements or bits at the top and adjacent front portions. The said cam means conveniently consist of appropriately shaped cam faces 69 and 70 provided, as shown, on a single block, or of two separate cam pieces suitably shaped and disposed.

Thus in the modification just described the

lower ends of the selecting elements or bits 58 are normally out of the range of the actuating cam 67, and selected elements or bits are pushed inwards into the range of the said cam.

5 The expression "knitting instrumentality" appearing in the appended claims is employed in a generic sense to include, where the context so admits, needles, needle actuating sliders, such as are used in knitting machines of the double 10 axially opposed needle cylinder type, or intermediate jacks which are interposed between the needles or sliders and the selecting elements.

What I claim then is:—

1. Pattern mechanism for knitting machines 15 of the independent needle type comprising, in combination, actuating means for effecting endwise movement of knitting instrumentalities, a carrier having grooves therein, selecting elements, one for each knitting instrumentality, 20 adapted to be pivotally mounted in said grooves and having selecting butts in different positions lengthwise thereon, selecting cam means adapted to operate upon said butts, a pattern device for controlling said selecting cam means so that the 25 latter operate selectively upon the selecting butts for the purpose of determining which of the knitting instrumentalities shall be subsequently moved endwise by the aforesaid actuating means, each of said selecting elements being adapted 30 in the region of its tail end to have operative relationship with a companion knitting instrumentality whereby when such elements are acted upon by the selecting cam means and make contact with the actuating means endwise movement of the corresponding knitting instrumentalities is effected, for the purpose herein set forth.

2. Pattern mechanism for knitting machines 40 of the independent needle type comprising, in combination, actuating means for effecting endwise movement of needles, a carrier having there- 45 in grooves, selecting elements, one for each needle, adapted to be pivotally mounted in said grooves and having selecting butts in different positions lengthwise thereon, selecting cam means adapted to operate upon said butts, a pattern device for controlling said selecting cam means so that the latter operate selectively upon the selecting butts for the purpose of determining which of the needles shall be subsequently 50 moved endwise by the aforesaid actuating means, each of said selecting elements being adapted in the region of its tail end to have operative relationship with a companion needle whereby when such elements are acted upon by the selecting cam means and make contact with the actuating means, endwise movement of the corresponding needles is effected, for the purposes herein set forth.

3. Pattern mechanism for knitting machines 60 of the independent needle type comprising, in combination, actuating means for effecting endwise movement of needles, a carrier having there- 65 in grooves, selecting elements, one for each needle, adapted to be pivotally mounted in said grooves and having selecting butts in different positions lengthwise thereon, a series of needle actuating instrumentalities, one for each needle, selecting cam means adapted to operate upon said butts, a pattern device for controlling said selecting cam means so that the latter operate 70 selectively upon the selecting butts for the purpose of determining which of the needles shall be subsequently moved endwise by the aforesaid actuating means, each of said selecting elements being adapted in the region of its tail end to 75

have operative relationship with the companion needle actuating instrumentality whereby when such elements are acted upon by the selecting cam means and make contact with the actuating means, endwise movement of the corresponding needles is effected, for the purpose herein set forth. 5

4. Pattern mechanism according to claim 1, wherein the selecting elements are disposed in front of the knitting instrumentalities in the same grooves, which latter are accordingly made sufficiently deep to accommodate both.

5. Pattern mechanism for knitting machines of the independent needle type comprising, in combination, actuating means for effecting end- 15 wise movement of knitting instrumentalities, a carrier having grooves therein, selecting elements, one for each knitting instrumentality, adapted to be pivotally mounted in said grooves and having selecting butts in different positions 20 lengthwise thereon, selecting cam means adapted to operate upon said butts, a pattern device for controlling said selecting cam means so that the latter operate selectively upon the selecting butts for the purpose of determining which of 25 the knitting instrumentalities shall be subsequently moved endwise by the aforesaid actuating means, each of said selecting elements being formed in the region of its tail end with a rear- 30 wardly projecting foot adapted to extend under the adjacent end of the associated knitting instrumentality whereby when such elements are acted upon by the selecting cam means and make contact with the actuating means end- 35 wise movement of the corresponding knitting instrumentalities is effected, for the purpose herein set forth.

6. Pattern mechanism for knitting machines of the independent needle type comprising, in combination, actuating means for effecting end- 40 wise movement of knitting instrumentalities, a carrier having grooves therein, selecting elements, one for each knitting instrumentality, adapted to be pivotally mounted in said grooves and having selecting butts in different positions 45 lengthwise thereon, selecting cam means for acting upon said butts and comprising a plurality of selecting cams individually movable to and from an operative position, a pattern device for controlling the movements of the said selecting cams so that the latter operate selectively upon the selecting butts for the purpose of determining which of the knitting instrumentalities shall be subsequently moved endwise by the aforesaid actuating means, each of said selecting 50 elements being adapted in the region of its tail end to have operative relationship with a companion knitting instrumentality whereby when such elements are acted upon by the selecting cam means and make contact with the actuating means, endwise movement of the corresponding knitting instrumentalities is effected, for the purpose herein set forth. 55

7. In a knitting machine of the independent needle type, pattern mechanism comprising, in 60 combination, a carrier having grooves therein, selecting elements, one for each knitting instrumentality, adapted to be pivotally mounted in said grooves and having selecting butts in different positions lengthwise thereon, selecting cam 65 means adapted to operate upon said butts, a pattern device for controlling said selecting cam means, actuating means for effecting endwise movement of knitting instrumentalities and adapted for action upon the lower ends of se- 70 75

lected selecting elements for the purpose of raising the latter to effect the aforesaid endwise movement so that the knitting instrumentalities are caused to function for patterning purposes, each of said selecting elements being adapted in the region of its tail end to have operative relationship with a companion knitting instrumentality whereby when such elements are acted upon by the selecting cam means and 5 make contact with the actuating means endwise movement of the corresponding knitting instrumentalities is effected, for the purpose herein set forth.

8. In a knitting machine of the independent needle type, pattern mechanism comprising, in combination, a carrier having grooves therein, selecting elements, one for each knitting instrumentality, adapted to be pivotally mounted in said grooves and having selecting butts in different positions lengthwise thereon, selecting cam means adapted to operate upon said butts, a pattern device for controlling 15 said selecting cam means so that the latter operate selectively upon the selecting butts for the purpose of determining which of the knitting instrumentalities shall be subsequently moved endwise by the aforesaid actuating means, and a cam located 20 behind the selecting elements in the region of their tail ends for pushing previously selected elements outwards preparatory to re-selection, each of said selecting elements being adapted in the region of its tail end to have operative relationship with a 25 companion knitting instrumentality whereby when such elements are acted upon by the selecting cam means and make contact with the actuating means, endwise movement of the corresponding knitting instrumentalities is effected, for 30 the purpose herein set forth.

9. Pattern mechanism according to claim 7, wherein the selecting elements are normally out of the range of the actuating means and the selecting cam means are adapted to cause selected elements to move pivotally into operative relationship with the companion knitting instrumentalities and into the range of the said actuating means.

10. In a knitting machine of the independent needle type, pattern mechanism comprising, in combination, actuating means for effecting endwise movement of knitting instrumentalities, a carrier having grooves therein, selecting elements, one for each knitting instrumentality, adapted to be pivotally mounted in said grooves and having selecting butts in different positions lengthwise thereon, selecting cam means adapted to operate upon said butts, a pattern device for controlling 5 said selecting cam means so that the latter operate selectively upon the selecting butts for the purpose of determining which of the knitting instrumentalities shall be subsequently moved endwise by the aforesaid actuating means and cam 10 means for action on selected selecting elements to restore the same to normal position preparatory to a re-selection being effected, each of said selecting elements being adapted in the region of its tail end to have operative relationship with a 15 companion knitting instrumentality whereby

when such elements are acted upon by the selecting cam means and make contact with the actuating means, endwise movement of the corresponding knitting instrumentalities is effected, for the purpose herein set forth. 5

11. In a knitting machine of the independent needle type, pattern mechanism comprising, in combination, actuating means for effecting endwise movement of knitting instrumentalities, a carrier having grooves therein, selecting elements, one for each knitting instrumentality, adapted to be pivotally mounted in said grooves and having selecting butts in different positions lengthwise thereon, selecting cam means adapted to operate upon said butts, a pattern device for controlling 15 said selecting cam means so that the latter operate selectively upon the selecting butts for the purpose of determining which of the knitting instrumentalities shall be subsequently moved endwise by the aforesaid actuating means, and a cam located 20 behind the selecting elements in the region of their tail ends for pushing previously selected elements outwards preparatory to re-selection, each of said selecting elements being adapted in the region of its tail end to have operative relationship with a 25 companion knitting instrumentality whereby when such elements are acted upon by the selecting cam means and make contact with the actuating means, endwise movement of the corresponding knitting instrumentalities is effected, for 30 the purpose herein set forth.

12. In a knitting machine of the independent needle type, pattern mechanism comprising, in combination, actuating means for effecting endwise movement of knitting instrumentalities, a carrier having grooves therein, selecting elements, one for each knitting instrumentality, adapted to be pivotally mounted in said grooves and having selecting butts in different positions lengthwise thereon, selecting cam means adapted to operate upon said butts, a pattern device for controlling 35 said selecting cam means so that the latter operate selectively upon the selecting butts for the purpose of determining which of the knitting instrumentalities shall be subsequently moved endwise by the aforesaid actuating means, a cam located 40 behind the selecting elements in the region of their tail ends for pushing previously selected elements outwards preparatory to re-selection, and a cam for returning selecting elements to the normal level after they have been acted upon by the actuating means, each of said selecting elements being adapted in the region of its tail end to have operative relationship with a companion knitting 45 instrumentality whereby when such elements are acted upon by the selecting cam means and make contact with the actuating means, endwise movement of the corresponding knitting instrumentalities is effected, for the purpose herein set forth. 50

13. Pattern mechanism according to claim 10, wherein the cam means for action on selected selecting elements to restore the same to normal position are arranged for action on the selecting elements at the top and adjacent front portions 65 thereof.

14. Pattern mechanism for knitting machines of the independent needle type comprising, in combination, actuating means for effecting endwise movement of knitting instrumentalities, a carrier having grooves therein, selecting elements, one for each knitting instrumentality, adapted to be pivotally mounted in said grooves and having selecting butts in different positions lengthwise thereon, intermediate jacks between 70

the knitting instrumentalities and the selecting elements, selecting cam means adapted to operate upon said butts, a pattern device for controlling said selecting cam means so that the latter operate selectively upon the selecting butts for the purpose of determining which of the knitting instrumentalities shall be subsequently moved endwise by the aforesaid actuating means, each of said selecting elements being adapted in the region of its tail end to have operative relationship with a companion intermediate jack whereby when such elements are acted upon by the selecting cam means and make contact with the actuating means, endwise movement of the corresponding knitting instrumentalities is effected, for the purposes herein set forth.

15. Pattern mechanism according to claim 14, wherein each of the intermediate jacks and the associated knitting instrumentality are formed in one piece.

20. 16. In a circular knitting machine of the double axially opposed needle cylinder type, pattern mechanism for assisting in the transference of pre-selected needles from one cylinder to the other, comprising, in combination, actuating means for effecting endwise movement of needles, a carrier having therein grooves, selecting elements, one for each needle, adapted to be pivotally mounted in said grooves and having selecting butts in different positions lengthwise thereon, a series of needle actuating instrumentalities, one for each needle, selecting cam means adapted to operate upon said butts, a pattern device for controlling said selecting cam means so that the latter operate selectively upon the selecting butts for the purpose of determining which of the needles shall be subsequently moved endwise by the aforesaid actuating means, each of said selecting elements being adapted in the region of its tail end to have operative relationship with the companion needle actuating instrumentality, whereby when such elements are acted upon by the selecting cam means and make contact with the actuating means, endwise movement of the corresponding needles is effected.

25. 17. In combination in a circular knitting machine, pattern mechanism comprising actuating means for effecting endwise movement of knitting instrumentalities, a carrier having grooves therein, selecting elements, one for each knitting instrumentality, adapted to be pivotally mounted in said grooves and having selecting butts in different positions lengthwise thereon, selecting cam means adapted to operate upon said butts, a pattern device for controlling said selecting cam means so that the latter operate selectively upon the selecting butts for the purpose of determining which of the knitting instrumentalities shall be subsequently moved endwise by the aforesaid actuating means, each of said selecting elements being adapted in the region

of its tail end to have operative relationship with a companion knitting instrumentality, whereby when such elements are acted upon by the selecting cam means and make contact with the actuating means, endwise movement of the corresponding knitting instrumentalities is effected, for the purpose herein set forth, and means for restricting patterning to prearranged portions circumferentially of knitted fabric.

30. 18. In a circular knitting machine of the independent needle type, in combination, pattern mechanism comprising actuating means for effecting endwise movement of knitting instrumentalities, a carrier having grooves therein, selecting elements, one for each knitting instrumentality, adapted to be pivotally mounted in said grooves, and having selecting butts in different positions lengthwise thereon, some of said selecting elements being provided with long tails and the remainder with shorter tails, selecting cam means adapted to operate upon said butts, a pattern device for controlling said selecting cam means so that the latter operate selectively upon the selecting butts for the purpose of determining which of the knitting instrumentalities shall be subsequently moved endwise by the aforesaid actuating means, each of said selecting elements being adapted in the region of its tail end to have operative relationship with a companion knitting instrumentality, whereby when such elements are acted upon by the selecting cam means and make contact with the actuating means, endwise movement of the corresponding knitting instrumentalities is effected, for the purpose herein set forth, a return cam for moving previously selected elements to normal position preparatory to re-selection and movable into different planes so that it can act on long and short tailed selecting elements, and means for moving said return cam so as to nullify the selective action according to requirements.

35. 19. For use in pattern mechanism for knitting machines, a needle selecting element comprising a stem, substantially straight from end to end, said stem having a projection extending rearwardly from its back at its upper end to constitute a fulcrum point, said stem having at least one frontal selecting butt and having a rearwardly extending butt adjacent its lower end, said stem having a downwardly extending tail at its lower end.

40. 20. The needle selecting element of claim 19, in combination with a needle actuating element having a jack-like extension at its lower end cooperating with the selecting element and consisting of a generally straight thin member having a forwardly curved lower end for engagement by the rearwardly extending butt of the selecting element.
